UNITED STATES PATENT OFFICE.

ALBERT P. SEYMOUR, OF SYRACUSE, NEW YORK.

DESIGN FOR AN ATTACHMENT-PLUG FOR ELECTRIC CUT-OUTS.

SPECIFICATION forming part of Design No. 29,708, dated November 22, 1898.

Application filed October 12, 1898. Serial No. 693,351. Term of patent 7 years.

To all whom it may concern:

Be it known that I, ALBERT P. SEYMOUR, a citizen of the United States, residing at Syracuse, in the county of Onondaga, in the State of New York, have invented and produced a new and original Design for an Attachment-Plug for Electric Cut-Outs, of which the following is a specification, reference being had to the accompanying drawings, forming part thereof.

My new design consists in the outline of an article of manufacture known as an "attachment-plug," which is made and sold as a complete article and is in common use with electric cut-outs for making and breaking the connection.

My design is best illustrated in Figure II of the accompanying drawings, which is a side elevation of a plug made according to my design, Fig. I being a top plan view.

The upper or cap portion of the plug is the characteristic feature of the design and is

formed of a wide smooth cylindrical band, unbroken by joint or projection, extending entirely around the cap, slightly beveled on ²⁵ its under edge and extending above into a slightly-flattened dome rising directly from the upper margin of the band.

In the drawings, 1 indicates the cylindrical flat band, 2 the dome, and 3 the slightly-beveled lower edge of the band. 4 is the lower portion or shank, formed with spiral grooves and a tapering end 5, with a slightly-projecting tip 6.

Having described my invention, what I ³⁵ claim as new, and desire to secure by Letters Patent, is—

The design for an attachment-plug for electric cut-outs, as herein shown and described.

ALBERT P. SEYMOUR. [L. S.]
